ICE CUBE RELEASE

Chancey B. Westra, Houston, Tex., assignor, by
mesne assignments, to General Motors Corpora-
tion, Detroit, Mich., a corporation of Dela-
ware

Application June 21, 1937, Serial No. 149,295

9 Claims. (Cl. 62—108.5)

The invention relates to ice trays and grids and more particularly to an assembly of the type that releases ice cubes from the tray and grid.

It is an object of the invention to provide an ice cube release mechanism for removing ice cubes from a tray and grid.

A further object is to provide an ice cube release mechanism which removes the ice cubes sequentially from one end of the tray to the other.

A further object is to provide a grid structure having transverse web members which are movable relative to the tray and to each other.

A further object is to provide a grid structure having transverse web members which are sequentially movable so that ice cubes are sequentially released and a predetermined number of cubes may be released and removed.

The foregoing objects, and others, will be apparent from the following description taken in connection with the drawings in which:

Fig. 1 is a plan view, partly in section, showing an ice tray and grid embodying the invention.

Fig. 2 is a sectional view taken on line 2—2 of Fig. 1.

Fig. 3 is a sectional view taken on line 3—3 of Fig. 1.

Fig. 4 is an elevation showing the ice tray in section and respective transverse webs in the positions that will be assumed when all ice cubes are released.

Fig. 5 is a detail view showing one of the web members.

Fig. 6 illustrates the construction of an actuating rod comprising an element of the invention.

Fig. 7 illustrates a central vertical section of a modified form of the invention showing parts in normal position.

Fig. 8 is a view similar to that shown in Fig. 7 but showing the relative position of parts when all ice cubes have been released.

Fig. 9 is a vertical section taken on line 9—9 of Fig. 7.

Fig. 10 is a vertical section taken on line 45 10—10 of Fig. 8.

In the drawings numeral 1 represents an ice tray or pan having a rolled upper edge 2, a depressed center portion 3 having side walls 8 and an inclined end wall 9. This tray is adapted to receive a grid generally designated as 4. The grid 4 comprises a longitudinal partition member 5 and transverse web members 6 which divide the tray into a plurality of cells 7 for the production of ice cubes, as is well known in the art.

The grid 4 is of particular construction, the longitudinal partition 5, in the embodiment shown in Figs. 1—4, being a channel shaped member of U-shaped cross section and having its ends closed by walls 10 and 11. In this manner the longitudinal dividing member comprises an open chamber adapted to receive certain actuating elements as will hereafter be described. The walls of member 5 are provided with recesses 12 near their upper edges and these recesses are adapted to swingably receive transverse web members 6, which will now be described.

The construction of web member 6 is best shown in Fig. 5. These web members comprise a flat plate having its side and bottom edges 15 and 16 of such contour that they fit in close juxtaposition to the side walls of the pan 1 when the device is in use. Each of web members 6 is provided with slots 17 and 18, whereby a tongue 19 is formed. These slots 17 and 18 are in such spaced relation that when the web member is placed upon the channel 5 the walls thereof will enter the slots, and the tongue 19 will therefore extend downwardly within the channel. These web members are positioned in the respective recesses 12 and it is obvious that the web members are thus swingably supported upon member 5. These web members 6 are also provided with small recesses 20 on their upper edges for a purpose that will be made apparent.

A lever 25 is pivotally mounted at one end thereof on a pin 26, which is carried by the partition 5. One end of the lever 25 is provided with ears 27, which extend outwardly to facilitate grasping of the lever by the hand. The opposite end of lever 25 extends downwardly within member 5 and is bifurcated to receive the flattened end 30 of an actuating rod 31, best shown in Figs. 2 and 6. The lever 25 and the actuating rod 31 are pivotally connected by a pin 32 passing therethrough.

By reference to Fig. 6 it will be noted that this actuating rod 31 is provided with a plurality of flattened sections 35 of progressively increasing length from the end opposite the connection to the handle 25. Each of the flattened portions 35 hence provides a pair of oppositely disposed shoulders 36 and 37. The outer or left end of the rod 31 is likewise provided with a downwardly extending tip at 38 so as to support the rod for sliding movement on the bottom of the pan.

The grid is assembled by placing the rod 31 within the channel or member 5 and affixing the lever 25 upon its pivot 26 therein. The outer or left end of the actuating rod 31, as seen in Fig. 6,

then rests upon the bottom of member 5. It is obvious with this construction that upward movement of lever 25 will cause actuating rod 31 to move longitudinally of member 5. The respective web members 6 are then placed in recess 12 of member 5 so that the tongues 19 will extend downwardly and the slots 21 will pass over the flattened portions 35 of rod 31. It is here noted that the flattened portions 35 are so positioned upon rod 31 that when the web members 6 are suspended in vertical position the respective tongues 19 will contact the forward shoulders 36 of the flattened portions 35.

By virtue of the progressive increasing length of flattened portions 35 it is believed obvious that movement of the lever 25 will cause the web members 6 to be progressively engaged by shoulders 37 whereby the web members are sequentially swung from their vertical position to accomplish the desired functioning of the device.

It should be noted that the grid 4 projects upward slightly above the top of the tray 1 and that hence the recesses 12 in the member 5 are above the top of the tray. This feature prevents water entering the channel member 5 in the tray. In order to assure sealing against the entry of water, however, a small sealing plate 40 is mounted in each recess 20 on the web 6 inside of the member 5. A thin gasket material 41 is inserted between plate 40 and the side walls of member 5. Each of these sealing plates 40 is provided with a central slot 43 to receive the upper edge of the web 6. Each of the sealing plates is also provided with an arcuate upper edge 39 in order that the plate may swing within the recess 12 and beneath a cap plate 42 which is affixed to the channel member 5, as by soldering, when the moving parts are assembled therein as already described.

Figs. 7 to 10 illustrate an alternative embodiment of the invention. In this modified form of the invention the longitudinal division member 5 comprises a plate member having downwardly extending V-shaped slots 50 in its upper edge. The transverse web members 6 are slotted centrally at 51 to straddle the longitudinal division member 5 and swingably rest upon the bottoms 52 of the V-shaped slots 50.

Bearing members 53 and 54 are attached to the upper edge of division member 5 at the opposite ends thereof to rotatably support a rod 55, which is held against longitudinal movement by means of a cam 56 and a collar 57 fixed thereto and bearing against the outer faces of bearing members 53 and 54, respectively. Web members 6 extend upwardly above the upper edge 58 of division member 5 as best seen in Fig. 9 and are provided with upwardly opening recesses to permit the passage of rod 55 therethrough.

Rod 55 is threaded throughout the major portion of its length and threaded plugs 60, having a groove 61 in their lower faces, are positioned thereon so that the groove 61 slidably engages the upper edge 58 of the division member 5, the forward or left-hand faces of plugs 60 being progressively spaced from the vertical side 62 of the V-shaped slots 50. It is here reiterated that the showing of the progressive displacement of parts in order to obtain sequential swinging of the web member 6 is greatly exaggerated for purposes of illustration.

Contacting the faces of web members 6 on the side opposite plugs 60 are washers 62, which are resiliently urged to the right in Figs. 7 and 8 by means of compression springs 63. In this manner

when the parts are in normal position as illustrated in Fig. 7 the web members are vertical whereby cubes will be formed when the liquid within the pan 1 is congealed.

5 The overhanging edge 65 of the tray 1 is provided with a downwardly extending support made integral therewith and comprising a vertical wall 66 and horizontal wall 67, the latter of which is apertured at 68 to receive a release pin 69 which, 10 as shown in Fig. 7, extends downwardly to the plane of the bottom of the tray 1. Intermediate its ends pin 69 is provided with a collar 70 affixed thereto and a compression spring 71 constantly urges the pin upwardly against cam 56, which 15 extends through an opening 72 in the overhanging edge 65. From this construction it is apparent that the position of pin 69 is determined by the longitudinal position of the arm 73 on rod 55.

20 The rod 55, springs 63 and blocks 60 are enclosed by an inverted channel member 74, which is secured in place by clamping the ends thereof downwardly about the periphery of bearing members 53 and 54 as best seen in Fig. 10.

25 The operation of the embodiment of the device shown in Figs. 1 to 6 is as follows:

With the lever 25 in position as shown in Figs. 1 and 2, the web members 6 swingably supported in a vertical position in the channel or partition 30 5 the tray 1 is filled with water to be frozen. After freezing has been effected and it is desired to remove a part or all of the cubes so formed, the assembly is removed from the freezing chamber and the lever 25 is grasped at 77 and moved 35 upwardly.

Initial movement of the lever causes the outermost web 6, shown at the left in Figs. 1, 2, and 4, to be first moved slightly when the shoulder 37 abuts the tongue 19 and release the cubes to the 40 left thereof because the movement of the web 6 forces the ice cubes against the inclined end wall 9 so that there will be a tendency to raise the cube from the tray as the bond with the tray and the web is broken due to movement of the web. A slight movement of the lever 25 will effect this release. Immediately after this first pair or set of cubes is released the successive web member will be moved to release the adjacent cubes. This releasing action will proceed progressively as the lever 25 is moved upwardly toward its final position when all cubes will have been released. The present invention is particularly advantageous in that its construction is such that pressure to release only one set of cubes at a time is 45 required so that no force of a substantial amount is required. One or more sets of cubes may be released as desired. The final position of parts when all cubes are released in the embodiment 50 illustrated in Figs. 1 to 6 is clearly illustrated in Fig. 4 wherein the progressively inclined positions of the series of web members is clearly shown. The inclination of the web members is greatly exaggerated in the drawings in order to 55 better illustrate the operation of the device of the invention.

60 In the form shown in Figs. 7 to 10, the normal position of parts is shown in Fig. 7. If it is desired to remove the tray and grid from the freezing chamber, handle 73 is turned slightly, whereupon releasing pin 69 is forced downwardly to 65 release the tray from the shelf within the freezing chamber. The tray and grid are then withdrawn from the chamber.

70 Further turning of the handle 73 causes the 75 upper edges of web members 6 to be sequentially

engaged by blocks 60 whereby sequential rocking of the web members about the bottoms 52 of the V-shaped slots 50 takes place and the ice cubes within the tray and grid are sequentially released as above described. A limited rotation of the handle 73 and its associated rod 55 will cause web members 6 to assume the positions shown in Fig. 8 when all ice cubes are released. It is to be noted that the web members 6, as shown in Fig. 8, are inclined to the left to effect the desired releasing action. It is to be understood, however, that the invention is not confined to this construction and mode of operation, as it is obvious that the relative position of parts may be such as to incline the web members 6 to the right and it is contemplated that such construction shall fall within the scope of the invention.

From the foregoing it is apparent that by the present invention any desired number of ice cubes may be released by terminating the movement of the actuating mechanism when the desired release has been effected. If less than all of the ice cubes are released, the actuating mechanism may be returned to its original position and the tray with the remaining cubes may be replaced in the freezing chamber for subsequent sequential release of the remaining ice cubes, or, water may be added to again fill the cells from which ice cubes have been removed.

It is believed obvious that the foregoing description discloses an invention providing an ice tray and grid assembly from which ice cubes may be released without heat. Furthermore, the invention provides a device which is simple and rugged and which will sequentially release ice cubes whereby operative stresses are minimized and cubes are completely released from the grid and tray in any desired number. While a preferred embodiment and a modification thereof are shown, it is obvious to those skilled in the art that the invention is not so limited but is susceptible to various changes without departure from the spirit of the invention, and it is desired that limitation shall be imposed thereon only as dictated by the prior art and the appended claims.

What is claimed is:

1. In an ice cube pan, a grid having a longitudinal division member of channel shape having recesses therein, transverse web members swingably supported in said recesses, each of said web members having a tongue portion extending downwardly into said channeled division member, a rod movably mounted within said division member and having shoulders thereon adapted to sequentially engage said tongue portions and swing the web members, and manually operable means extending into the channel of said division member for moving said rod to engage the web members.

2. In an ice cream pan, a grid having a hollow longitudinal division member, transverse web members swingably supported thereon, each of said web members having a tongue portion extending into said division member, sealing means between said web members and the walls of said division member, an actuating bar movably mounted within said division member and having shoulders thereon adapted to engage said tongue portions to swing the web members and manually operable means connected to said actuating bar and extending outwardly from the division member.

3. In an ice cube pan, a grid having a hollow division member, transverse web members swingably supported on said member and having

tongues extending therein, an actuating bar within said division member having means adapted to engage said tongues to swing said web members, and a manually operable member extending into said division member for moving said bar whereby ice cubes are released from the grid and pan.

4. A grid member for ice trays including a longitudinal division member of channel shape, web members extending transversely of and swingably supported on, said division member and having an arm portion extending into the channel of said division member, and means for sequentially swinging said web members from vertical position to release part or all of the ice cubes from the tray and grid.

5. A grid for ice trays including a hollow, longitudinal division member having openings therein, web members extending transversely of and swingably supported in said openings, each of said web members having a tongue extending downwardly within said division member, and a manually movable bar within the division member having shoulders for sequentially engaging said tongues to swing the web members, whereby ice cubes are sequentially released.

6. In combination an ice cube pan, a grid removably fitting in said pan, said grid having a longitudinal division member, transverse web members supported upon said division member for swinging movement about axes below the upper edge of the member, a rod rotatably mounted upon said division member and extending longitudinally thereof, a tray release bar movably mounted on the exterior of said pan, means on said rod for moving said release bar downwardly upon initial rotation of the rod, and additional means on said rod engaging said transverse webs for swinging the webs after the tray has been released by movement of said release bar.

7. A freezing device adapted to be removably supported on a cooling element, said freezing device including a tray and a grid disposed in the tray for dividing the interior thereof into a plurality of ice block forming compartments, said grid having a longitudinal wall and a plurality of transverse walls movable relative thereto, and a single means movably mounted on said device for causing movement of said device upwardly of its support on the cooling element and for progressively imparting force to said transverse grid walls to move same in succession relative to said longitudinal grid wall to sequentially break the ice bond between ice blocks and said grid and tray.

8. A freezing device adapted to be removably supported on a cooling element, said device comprising a tray and a unitary removable grid structure disposed in the tray for dividing the interior thereof into a plurality of ice block forming compartments, said grid structure having a longitudinal wall and a plurality of walls extending transversely through the plane of said longitudinal wall and interlocked therewith for movement relative thereto, and a single means movably mounted on said device for causing movement of said device upwardly of its support on the cooling element and for applying force to said transverse grid walls to move same relative to said longitudinal grid wall to break the ice bond between ice blocks and said grid and tray.

9. A freezing device adapted to be removably supported on a cooling element, said device comprising a tray and a unitary removable grid struc-

ture disposed in the tray for dividing the interior thereof into a plurality of ice block forming compartments, said grid structure having a longitudinal wall and a plurality of walls extending transversely through the plane of said longitudinal wall and interlocked therewith for movement relative thereto, and a single means movably mounted on said device for causing move-

ment of said device upwardly of its support on the cooling element and for applying force to the upper portion of said transverse grid walls in a direction lengthwise of said grid structure to tilt same relative to said longitudinal grid wall for breaking the ice bond between ice blocks and said grid and tray.

CHANCEY B. WESTRA.
